UNITED STATES PATENT OFFICE

93,168

DESIGN FOR A MASK FOR TYPEWRITING MACHINES

John J. Kittel, St. Albans, N. Y., assignor to Royal Typewriter Company, Inc., New York, N. Y., a corporation of New York

Application April 28, 1934, Serial No. 51,572

Term of patent 14 years

To all whom it may concern:

Be it known that I, JOHN J. KITTEL, a citizen of the United States, residing at St. Albans, in the county of Queens and State of New York, have invented a new, original, and ornamental Design for a Mask for Typewriting Machines, of which the following is a specification, reference being had to the accompanying drawing, forming part thereof.

In the accompanying drawing, the figure is a perspective view of a mask for typewriting machines showing my design.

I claim:

The ornamental design for a mask for typewriting machines substantially as shown.

JOHN J. KITTEL.
